UNITED STATES PATENT OFFICE.

LOUIS E. LAURENT, OF TRENTON, NEW JERSEY.

DUMB-WAITER AND ELEVATOR.

No. 851,175.

Specification of Letters Patent.

Patented April 23, 1887.

Application filed May 12, 1905. Serial No. 260,932.

To all whom it may concern:

Be it known that I, LOUIS E. LAURENT, a citizen of the United States, residing at Trenton, in the county of Mercer and State of New Jersey, have invented new and useful Improvements in Dumb-Waiters and Elevators, of which the following is a specification.

This invention relates to improvements in elevators and particularly to that class of elevators which are commonly called dumb waiters and which are useful for carrying various articles from floor to floor in buildings.

The object of the invention is the provision of an elevator or dumb waiter which may be electrically operated and which can be set in motion from any floor in a building and be caused to automatically stop at any other floor according to the intention of the operator.

It is a further object of the invention to provide means in connection with the controlling mechanism which shall indicate at the different floors or stations of the building or structure in which the elevator is incorporated at what point the elevator is at any time when stationary or in which direction it is moved when in motion.

With these and other objects in view the invention comprises certain novel constructions, combinations and arrangements of parts as will be hereinafter fully described and claimed.

In the accompanying drawings: Figure 1 is a top plan view of the mechanism for driving the elevator, the controller for starting the mechanism and automatically stopping it being also shown. Fig. 2 is a front elevation of the same. Fig. 3 is an enlarged elevation of the starting controller. Fig. 4 is a view of a portion of the controller on a larger scale than shown in Fig. 3, a portion of the mechanism being shown in elevation and a portion in central section. Fig. 5 is a side elevation of the controller, the contact disc which is used in connection therewith being removed, and a portion of one of the contact rings which is connected with the line wire, being partially broken away. Fig. 6 is a detail sectional view taken upon the line *a—b* of Fig.

Fig. 7 is an end elevation of the controller without the contact disc. Fig. 8 is a side elevation of the contact disc showing the face which is engaged by the contacts of the controller. Fig. 9 is a similar view of the other side of the said disk. Fig. 10 is a side

elevation of an elevator or dumb waiter constructed in accordance with the present invention and as installed in a structure for operation. Fig. 11 is a detail sectional view taken horizontally through the wall of a building showing one of the stations at which the elevator is stopped, the structure being designed for use in one apartment only at that station. Fig. 12 is a similar view but showing the elevator as accessible from both sides of the wall. Fig. 13 is a front elevation of an indicator located at one of the floors or stations, the controller operating arm being also shown. Fig. 14 is an enlarged top plan view of the said controller operating arm with its actuating pinion, the wall and the rack bar being shown in section. Fig. 15 is a detail view showing in side elevation a portion of the rack bar and an actuating pinion meshing therewith. Fig. 16 is a diagrammatic view illustrating the wiring of the mechanism.

In many large buildings or even medium sized ones it is of great advantage to have an automatically operating elevating mechanism or dumb waiter for carrying various articles from floor to floor without the necessity of using the stairs or a passenger elevator. It is particularly advantageous to provide apartment houses or like buildings with such a mechanism, especially where the mechanism can be controlled by the parties desiring to use it, without the necessity of having an attendant at hand for controlling the mechanism. It is within the contemplation of the present invention to provide such an elevator or dumb waiter the mechanism of which is operable by an electric current, the said current being only called into play when it is necessary to use the elevator, there thus being no unnecessary waste in the consumption of the current. The mechanism is so arranged that it may be controlled from any floor or station in the building and the car of the elevator can be sent from any floor or station to any other floor or station as the operator may desire. The mechanism is also provided with indicating means located at each floor or station in the building which will show in what position the car of the elevator is occupying.

In the drawings, I have illustrated a practical manner of carrying the invention into effect, and will describe my improvement with reference to the same. Located in the

basement or upon any other floor of a building or structure is a motor 1, which may be of any desired form and strength, the said motor being capable of driving a shaft 2 which is provided with a worm for actuating a worm wheel, as 3, the said worm wheel being connected with the shaft 4 of a drum 5. This mechanism may all be of the usual type employed with elevating mechanism and the drum 5 is designed for winding and unwinding the rope or cable 6 which is connected with the elevator car 7, the said rope or cable usually passing over a pulley or drum 8 located above the highest point which is to be reached by the car. Adjacent to the motor and the drum 5 is mounted what is usually termed a self-starter, as at 9. The self-starter 9 is also constructed in any usual or ordinary manner, the same being provided with resistances which are automatically cut out, for increasing the speed of the motor, by means of a switch arm 10 which is drawn successively over contact points 11 by means of a solenoid or other magnet 12. The switch arm 10 is provided with a dash pot or a spring mechanism, as at 13, for returning it to its normal position when the motor is not actuated by the electric current.

As shown in Fig. 10 the car 7 may be arranged to travel in a suitable shaft 14, formed in the walls of the building, and openings 15 are provided at points where it is designed to have the car stop. As shown in Fig. 11, the opening at one of said stations may be provided with a door 16 which the operator opens for gaining access to the car of the elevator. Guides 17 are arranged in the shaft 14 for properly directing the movement of the car. The controller operating mechanism with its indicator is located to one side of the door and its mechanism will be hereinafter fully described. As shown in Fig. 11 the elevator is only accessible from one side. The elevator may, however, be made accessible from opposite sides, as shown in Fig. 12, as when it is made to run within a partition wall separating two apartments. In this instance two doors as 18 are provided, one upon one side of the elevator and the other upon the other side. When running the elevator in a wall of this character the car, as 19, is preferably made open upon both sides. The controller operating mechanism and the indicators are also made to extend upon the opposite faces of the partition wall.

The mechanism for operating the controller comprises a rod 20, which is provided at suitable intervals with rack bar sections 21, the said rack bars being arranged opposite the openings 15 in the shaft 14. A pinion 22 meshes with the teeth of each rack bar and is carried by a shaft 23 mounted adjacent to the rack bar, the end of the said shaft extending outside the wall and carrying an operating handle or arm 24. By

moving the arm 24 the pinion 22 may be moved for actuating the rack bar 21 and correspondingly raising or lowering the rod 20. The upper end of the rod 20 is preferably connected with a counter-balance weight 25, a cable 26 joining the said weight and the upper end of the rod and passing around a supporting pulley 27 mounted adjacent to the pulley 8. The lower end of the rod 20 extends to a point in close proximity to the controller of the motor and may be connected therewith in any suitable or desired manner. I have shown, and prefer to use for this purpose, a rack bar 28 secured to the lower end of the rod 20 and meshing with a gear wheel 29 which is connected with the controller. A guide 30 holds the rack bar in contact with said gear as clearly illustrated in Fig. 3. The arm 24 at each station or floor is made to travel over an indicating plate 31 and the said plate is provided with marks designating the different stations or floors, as for instance "B" for basement, and 1, 2, 3, 4, 5, 6, etc., referring to the floors in the building. It will be observed that by moving anyone of the handles or arms 24, the bar 20 will be raised or lowered, correspondingly effecting the controller, and since the pinions 22 of all of said arms or handles are all in mesh with the rack bars of said rod 20, all of the said arms or handles will be moved in exact correspondence with each other. It thus follows that when one of the arms or handles 24 is moved to B all of the said handles will be brought simultaneously over the same indication upon their respective indicator plates 31. If a handle is moved to the indication 2 all of the handles will point to the same indication.

The controller actuating mechanism just described is connected with a controller, as above stated, and the structure of the controller, which will now be described, is such that when anyone of the handles 24 is moved to a certain indication or number the elevator motor will be started and caused to operate long enough to bring the car opposite the floor or station designated by the said indication, when the motor will be automatically stopped and the car will be checked opposite the proper floor or station. If it is desired to return the car to its original position or to a lower floor one of the handles is moved opposite the proper indication or number and the motor will be reversed for carrying the car to the desired point. The controller referred to comprises a movable member 32 which is movably mounted upon a shaft 33, the said member being provided with a hub 34, for this purpose. The shaft 33 is mounted in bearings adjacent to the drum 5 and the said shaft preferably extends at right angles to the shaft 4 of the said drum 5. A worm wheel 35 is secured to the shaft 33 and meshes with a worm 36

rigidly secured to the shaft 4. The shaft 33 is thus rotated by the shaft of the drum 5 whenever the said drum is driven by the operation of the motor 1. The hub 34 is loosely mounted on the shaft 33 so that it does not turn with the shaft. The gear 29 is rigidly secured to the said hub 34 so that when the said gear is moved by the raising or lowering of the rack bar rod 20 the hub 34 and the movable member 32 of the controller will be correspondingly moved about the shaft 33. In order to hold the said movable member in the various positions to which it may be brought, a brake drum or pulley 37 is secured to the said hub 34 and a band brake 38 is arranged to bear upon the periphery thereof, a suitable weighted lever 39 being used to maintain a proper tension upon the band brake 38. The friction of the brake will be sufficient to hold the movable member 32 in its various positions but will not be sufficient to make it difficult to move the said member through the agency of the operating handles 24 and the rack bar rod 20.

The movable member 32 is made up of a frame projecting oppositely from the hub 34 to a suitable distance and carrying sliding blocks or members 40 and 41. These slides 40 are provided with guide-ways or grooves 42 in their side walls which engage inwardly projecting guides 43 formed upon the framing of the member 32. Movably mounted in the slides 40 and 41 are contact plugs 44, 45, 46, 47 and 48. The slide 40 carries three of the said plugs, namely 44, 45, and 46, while the slide 41 carries the other two contact plugs 47 and 48. The said plugs are all insulated from their respective slides by being movably held in position by face plates 49 and 50 which are insulated from the body portions of the slides, such insulation being shown at 51 and 52. The inner ends of the plugs are, however, electrically connected, the three plugs 44, 45, and 46, being joined in this manner by conductors 53 and 54, while the plugs 47 and 48 are connected by a conductor 55. The contact plugs 47 and 48 are also electrically connected with a contact ring 56 which is mounted upon the movable member 32 but is separated therefrom by insulation, as at 57. The connection between the ring 56 and the said plug is preferably effected by pivoted links 58 and 59 so that the said plugs may move with their slide 41 without destroying their electrical connection with the said ring 56.

The slides 40 and 41 are normally drawn toward the shaft 33 by the action of springs 60 which surround pins or bolts 61 carried by a cross-bar 62. The said cross-bar 62 of each slide 40 and 41 is rigidly secured to the end of said slide and the pins or bolts 61 project inwardly therefrom, passing through apertured lugs 63 which project from the mov-

able member 32. The springs 60 are shouldered against said lugs 63 and also against nuts 64 secured to the ends of the pins or bolts 61. The tendency of the said springs is thus to pull the slides inwardly as above intimated.

It is desirable to lock the slides in their outermost positions when the elevator mechanism is in operation, the locking means being such that the slides may be easily released therefrom when the mechanism is automatically stopped and the parts come to rest. The locking means referred to preferably consists of spring actuated bolts 65 which extend transversely across the ends of the movable member 32 having bearings in 30 projections formed thereon, the said bolts being provided with slots 66 opposite the ends of the slides 40 and 41. The said slots are adapted to receive projecting hooks 67, which extend from the ends of the slides 40 and 41, when the said slides are in their outermost positions. The bolts 65 are held in engagement with the said hooks 67 by means of springs 68 which bear against collars 69 secured to the said bolts. The contact ring 90 95 56 is engaged by a contact standard 70 which rises from the base of the apparatus and which is electrically connected with the feed or line wire coming from the source of electrical supply. This is diagrammatically indicated in Fig. 16.

Operating in conjunction with the slides carrying the contact plugs is a contact disc 71 which is rigidly secured to the shaft 33 so as to turn therewith when the motor is in operation. The said disc is provided upon its face, which is next to the movable member 32, with segmental plates or contact strips 72, 72^a, 73, 73^a, and 74, 74^a. Spaces are left between the adjacent ends of these segmental contact plates as indicated at 75, and these spaces are preferably in alignment with each other and also in alignment with the contact ends of the plugs carried by the slides 40 and 41 when the elevator actuating mechanism is stationary. The spaces 75 are flared inwardly toward the center of the disc, as clearly shown in Fig. 8, and a corresponding flare is given to the contact ends of the plugs 44 to 48. It will thus be seen that 115 when the said plugs are brought opposite the spaces 75 and moved quickly toward the center of the disc 71 by the action of the spring 60, that the contact between the said plugs and the segmental contact plates of the disc will be readily and quickly broken. When 120 the movable member 32 is swung to one side or the other upon the shaft 33 the contact plugs will be brought into engagement with the contact plates of the disc 71 for completing the proper electrical circuits through the elevator actuating mechanism. The contact plugs are forced into firm contact with the contact plates of the disc 71 by means of springs 76 which surround the stems of the 130

4
said plugs and bear against the inner faces of the walls of the slides 40 and 41. This structure is clearly shown in Figs. 4 and 6.

The contact plates on the inner face of the disc 71 are firmly secured thereto by being bolted or riveted to segmental plates 77, 77^a, 78, 79, and 79^a, which are located upon the outer face of the said disc 71. The said disc 71 is preferably made of soapstone, slate or other insulating material and the rivets or bolts which connect the segments on its opposite faces pass through the said disc as shown in Fig. 4 and electrically connect corresponding plates upon the opposite faces of the discs. The segmental plate 77 is provided with a binding post 77^b, and the plate 77^a with a binding post 77^c for permitting of the said plates being connected with the self-starter solenoid 12. Such connection is indicated in the diagrammatic view, Fig. 16, as by wires or conductors 80 and 81. The segmental plate 78 is provided with a binding post 78^a which is connected by a conductor 78^b with the field magnet 82, as indicated in Fig. 16. The current passes from the conductor 78^b through one winding of the field 82 and through a conductor 83 to the resistances of the self-starter. The plates 79 and 79^a are provided with binding posts 79^b and 79^c which are connected by conductors 84 and 84^a with the winding of the armature 85, as shown in Fig. 16. The said disc 71 is thus provided with the proper connection necessary for exciting starting and running the motor in the operation of the elevator. The disc 71 is also provided with means for moving the slides 40 and 41 outwardly when contact is to be made between the plugs of the movable member 32 and the contact plates of the disc 71. This means consists in an annular projection or rib 86 formed upon the hub 87 of the disc 71 which is arranged in alignment with the inner ends of the said slides 40 and 41. These inner ends carry anti-friction rollers 88 and 89 which travel upon the periphery of the annular projection or rib 86, and normally hold the slides in their outer positions.

The annular disc or rib 86 is provided with 50 oppositely arranged depressions or recesses 90 which are properly located to receive the anti-friction rollers 88 and 89 when the slides 40 and 41 are moved inwardly for breaking the contact made by the plugs with the plates of the disc 71. The said recesses 90 are therefore arranged in alignment with the spaces 75 as clearly shown in Fig. 8. Since it is necessary also to unlock the slides 40 and 41 in order that they may be moved inwardly, the disc 71 is provided with projecting cam surfaces 91 arranged opposite the spaces 75 and also arranged in the path of the bolts 65. When the ends of the bolts 65 engage and ride upon the cams 91 they will be forced against the action of the springs 68

sufficiently to release the hooks 67 and permit the said slides to move inwardly. It will be seen that the slides are thus unlocked by the cams 91 at a proper time to permit the anti-friction rollers 88 and 89 to drop into the recesses 90, the contact plugs being thus instantly moved out of contact with the plates on the inner surface of the disc 71. The unlocking cams 91 and the recessed annular projection or rib 86 operate simultaneously when the plugs are opposite the spaces 75. The contact plates upon the inner face of the disc 71, it will be seen, are arranged in pairs upon the opposite sides of the spaces 75 and are so connected, as shown in Fig. 16, that when the contact plugs engage the plates upon one side of said spaces the motor will be actuated in one direction and when they engage the other set of plates, the motor will be reversed. The course of the currents as they are affected by this movement of the plug carrying member in one direction or the other will be clearly understood by reference to Fig. 16. In this figure the feed or line wire 92 is shown which is connected with the contact standard 70. A branch wire 93 also extends from the said feed wire 92 to a winding in the field of the motor, as at 94. The said winding is also connected by a conductor 95 with the return line wire 96.

When the controller is moved to cause the elevator to be carried upwardly, the contact plugs 44, 45, and 46 will be moved to the position indicated in full lines in Fig. 16, so as to engage the three contact segments on the disc 71 which lie upon one side of the gap or spaces 75, while the contact plugs 47 and 48 which are connected with the feed wire through the post 70 and the ring 56, will engage the outer and innermost contact segments 72 and 74 upon the other side of said spaces 75. With the parts in this position it will be seen that a current of electricity will flow from the feed wire 92 through the standard 70 to the contact plugs 47 and 48. The part of the current which is thus delivered from the plug 47 to the segmental contact plate 74 will be directed through the conductor 84 which is connected with the end of the contact piece 74 to one end of the armature 85 and passing thence in one direction through the said armature will be delivered by the other conductor 84^a to the contact segment 74^a on the opposite side of the spaces 75. The current will then pass from the plug 46 to the plug 45, thus reaching the contact segment 73^a, whence it passes to the segment 78 on the other side of the disc 71 and through the conductor 78^b to the winding 82 of the motor field, thence through the conductor 83 to the resistances of the self-starter and through the movable arm 10 thereof to the return line wire 96, completing the circuit. At the same time a portion of the current passes from the contact plug 48 to the seg-

ment 72, thence through conductor 80 to the magnet or solenoid 12, returning through the conductor 81 to the segment 72^a, and reaching the segment 73^a through the connected 5 contact plugs 44 and 45. At this point the return of both portions of the current is the same through the conductor 78^b, field winding 82, conductor 83, rheostat and thence to the line wire 96.

10 As above pointed out the winding 94 of the motor field is connected in shunt with the line wires by the conductors 93 and 95 so that the said field is always properly excited for facilitating the operation of the motor. When 15 the controller is moved so as to reverse the motor and cause the car of the elevator to descend the direction of the currents is somewhat changed and the change is indicated upon the diagram in Fig. 16 by dotted lines 20 showing the position of the plugs 47 and 48 and of the plugs 44, 45, and 46, and dotted arrows are also used for showing the direction in which the current flows, full line arrows having been employed in showing the 25 direction of the current above traced. When the motor is reversed it will be observed that the contact plugs 47 and 48 are so located that they engage the contact segments 72^a and 74^a and the current as it comes from the 30 feed wire 92 passes through the said contact plates 74^a and 72^a in a reverse direction through the armature 85, causing it to reverse in the opposite direction from that in which it previously revolved, the current also 35 passing in a reverse direction through the solenoid 12. Of course the effect upon the solenoid is the same whether the current passes through it in one direction or the other but the important result gained by the 40 movement of the parts just described is in the reversing of the armature of the motor.

The operation of the mechanism will now be described. The elevator may be considered at rest at the lower end of the shaft with 45 the operating and indicating handle pointing at B. If a party upon the third floor desires to use the elevator it is only necessary for him to grasp the handle at his floor and turn it until the indication 3 is reached. This 50 will cause a swinging of the movable plug carrying member 32 about the shaft 33, through the agency of the rod 20 and the rack 28 which engages the gear 29 of said movable member 32. The movable member 55 will be moved over the face of the disc 71 a distance corresponding to the movement of the handle over the indicating disc 31. Upon the movement of the member 32 the slides 40 and 41 will be forced outwardly by the riding 60 of the anti-friction rollers 88 and 89 upon the elevated portions of the annular projection or rib 86. The bolts 65 will at the same time leave the cam 91 and be permitted to engage the hooks 67 for holding and locking the 65 slides in their outermost positions. The lugs

44, 45, 46, 47, and 48 will be brought into contact with the contact segments of the disc 71, and the circuits through the motor and self-starter will be established causing the gradual starting and increased continued 70 movement of the elevator until it reaches the desired floor. By the time the car of the elevator has reached the third floor the disc 71 will have been moved by the motor a sufficient distance to bring the spaces 75 opposite the contact plugs 44 to 48 and the locking bolts will then release the slides 40 and 41 and they will drop into the recesses 90 causing a breaking of the circuits and a stopping 75 of the elevator. If the elevator is to be returned to the basement, the operator moves the handle 24 to the indication B and this will move the member 32 as far in the opposite direction as it was originally moved in the other direction, establishing a reverse 80 current through the motor and causing an unwinding of the drum 5 until the car reaches the basement, by which time the disc 71 will have brought its circuit breaking spaces 75 opposite the contact plugs, and the mechanism 85 will be stopped. It will be observed that since all of the handles 24 at the different floors in the building are connected by their respective pinions with the same rod 20 that any movement in one of the handles will be 90 shown by all of the other handles, since they will be correspondingly moved with respect to their indicating plates. It will also be observed that an operator at any one of the 95 floors may not only bring the elevator car to 100 his own floor but may send it to any floor below or above his own merely by moving the handle 24 at his own floor.

A mechanism of this character is especially useful in buildings like the modern apartment house for it affords means for any inmate of the building to send articles, materials, or other things to the basement or to other floors of the building under his own control, and if it is desired to have the janitor of the building in the basement procure and send articles of any kind it is only necessary to communicate with the janitor through speaking tubes, telephones or like apparatus, when the object may be accomplished, the 105 elevator being operated either by the party at his own floor or by the janitor in the basement. The uses of the device will be readily understood and its utility and adaptability to the circumstances of various buildings 110 will be well understood. Of course the size of the elevating mechanism may be varied to suit the various circumstances under which it is to be used. If the mechanism is to be employed in the place of an ordinary dumb 115 waiter the apparatus need not be made of great size and can usually be constructed so that the car can be accommodated within the walls of the building or other structure. In the event of the apparatus being used for 120 125 130

large articles or heavy freight it may be necessary to provide a specially constructed well or shaft in which the car may be operated, all within the spirit of the invention. It will be seen that the electric current is only used when the car is moving from place to place, the current being cut off from the mechanism when the car is stationary.

It will be seen that notwithstanding the great utility of the mechanism and the adaptability with which it may be applied to building or various structures, that the structure is exceedingly simple and not such as to readily get out of order. It is also economical in structure and in operation. Of course it will be understood that I consider all minor changes in the details of construction as well within the spirit of my invention.

Having thus fully described my invention, what I claim as new and desire to secure by Letters Patent, is:

1. An elevator mechanism, comprising a driving apparatus, a controller, comprising a contact carrying member, a circuit completing member mounted adjacent thereto and provided with contact plugs, means for moving the said plugs in a radial direction for making or breaking circuits through the driving mechanism, and means causing one member of the controller to be moved equally with the other member for determining the extent of movement of the elevator.

2. An elevator mechanism, comprising a driving apparatus, a controller therefor having a movable plug carrying member, and a movable circuit maintaining member and radially operable slides for carrying the plugs of the plug carrying member.

3. An elevator mechanism, comprising a driving apparatus, a controller therefor, having a movable member, contact plugs carried by said movable member, a circuit maintaining member also forming a part of said controller and spring actuated slides mounted on the plug carrying member and carrying said plugs into and out of contact with the circuit maintaining member.

4. An elevator mechanism, comprising an electrical driving apparatus, a controller therefor made up of a circuit maintaining member operable in connection with the driving apparatus, a swinging member mounted adjacent to the circuit maintaining member, slides movably mounted in said swinging member, circuit completing contacts carried by said slides, and means for locking the slides in contacting position.

5. An elevator mechanism, comprising a driving apparatus, a controller made up of a contact maintaining disc operable by the driving mechanism, a movable circuit completing member, slides carried thereby, contacts projecting from the slides, and an annular cam surface controlling the position of the said slides.

6. An elevator mechanism, comprising a driving apparatus, a controller having a circuit maintaining member geared with the driving apparatus, contact segments carried thereon and separated by circuit breaking spaces, a rotatable contact making member operable in connection with said circuit maintaining segments, the movement of the circuit making member in one direction or the other causing the driving mechanism to move the elevator in one direction or the other, as the case may be, and means to move the contact making member radially to break the circuit.

7. An elevator mechanism, comprising a driving apparatus, a controller made up of a circuit maintaining disc having segmental plates mounted thereon and separated by flaring spaces, a second movable member mounted adjacent to the disc and carrying V-shaped plugs, means for moving the said plugs against the contact segments and means for drawing the said plugs in a radial direction when the plugs are opposite the said flaring spaces to quickly break the electrical circuits passing through the apparatus.

8. An elevator mechanism, comprising a driving apparatus, a controller made up of a rotating member having oppositely arranged sets of circuit maintaining segments, means for connecting the two sets of segments so that one will accomplish a reversal of the circuit through the driving mechanism from the direction in which the circuit is established by the other set, and a movable circuit completing member forming a part of said controller and rotatably movable adjacent said segment and movable radially to break the circuit.

9. An elevator mechanism, comprising a driving apparatus, a circuit controller operating in conjunction therewith and made up of a movable circuit maintaining contact member, a movable circuit establishing member, circuit establishing plugs carried by said latter member, and a circuit receiving ring electrically connected with said plugs, the said rings receiving the energizing current from a line wire.

10. An elevating mechanism, comprising a driving apparatus, a controller therefor made up of a segment carrying disc, opposite sets of segments arranged upon said disc, a movable plug carrying member, plugs carried thereby and arranged in alignment with each other and capable of being brought into alignment with the spaces between the opposite sets of segments for breaking the circuits which may be established through the driving apparatus, and a plug controlling cam carried by the said disc having depressions opposite the said spaces, the said depressions permitting the plugs to move away from the segments when opposite said spaces.

11. In an elevator, an electrically operated

winding drum, a shaft rotated by said drum, a contact disk rigidly mounted upon said shaft, a controller member rotatably mounted upon and rotatable independently of the shaft, contact blocks carried by the rotatable member and in contact with the disk, independently located means for moving the rotatable member in either direction, means completing a circuit for rotating the shaft in the same direction traversed by the rotatable member, and means for breaking the circuit

when the shaft has rotated through an arc equal to the arc of movement of the rotatable member.

In testimony whereof I have affixed my signature, in presence of two subscribing witnesses.

LOUIS E. LAURENT.

Witnesses:

EDWARD B. DURHAM,
CLARENCE E. SPRAGUE.
